CLAIM

The ornamental design for a garment, as shown and described.

DESCRIPTION

FIG. 1 is a front perspective view of a garment showing our new design according to a first embodiment.

FIG. 2 is a rear perspective view of the garment shown in FIG. 1.

FIG. 3 is a front view of the garment shown in FIG. 1.

FIG. 4 is a rear view of the garment shown in FIG. 1.

FIG. 5 is a right-side view of the garment shown in FIG. 1.

FIG. 6 is a left-side view of the garment shown in FIG. 1.

FIG. 7 is a top view of the garment shown in FIG. 1.

FIG. 8 is a bottom view of the garment shown in FIG. 1.

FIG. 9 is a front view of the garment shown in FIG. 1 when in use.

FIG. 10 is a rear view of the garment shown in FIG. 1 when in use.

FIG. 11 is a front perspective view of the garment shown in FIG. 1 when in use.

FIG. 12 is a rear perspective view of the garment shown in FIG. 1 when in use.

FIG. 13 is a front perspective view of the garment showing our new design according to a second embodiment.

FIG. 14 is a rear perspective view of the garment shown in FIG. 13.

FIG. 15 is a front view of the garment shown in FIG. 13.

FIG. 16 is a rear view of the garment shown in FIG. 13.

FIG. 17 is a right-side view of the garment shown in FIG. 13.

FIG. 18 is a left-side view of the garment shown in FIG. 13.

FIG. 19 is a top view of the garment shown in FIG. 13.

FIG. 20 is a bottom view of the garment shown in FIG. 13.

FIG. 21 is a front view of the garment shown in FIG. 13 when in use.

FIG. 22 is a rear view of the garment shown in FIG. 13 when in use.

FIG. 23 is a front perspective view of the garment shown in FIG. 13 when in use.

FIG. 24 is a rear perspective view of the garment shown in FIG. 13 when in use.

FIG. 25 is a front perspective view of the garment showing our new design according to a third embodiment.

FIG. 26 is a rear perspective view of the garment shown in FIG. 25.

FIG. 27 is a front view of the garment shown in FIG. 25.

FIG. 28 is a rear view of the garment shown in FIG. 25.

FIG. 29 is a right-side view of the garment shown in FIG. 25.

FIG. 30 is a left-side view of the garment shown in FIG. 25.

FIG. 31 is a top view of the garment shown in FIG. 25.

FIG. 32 is a bottom view of the garment shown in FIG. 25.

FIG. 33 is a front view of the garment shown in FIG. 25 when in use.

FIG. 34 is a rear view of the garment shown in FIG. 25 when in use.

FIG. 35 is a front perspective view of the garment shown in FIG. 25 when in use.

FIG. 36 is a rear perspective view of the garment shown in FIG. 25 when in use.

FIG. 37 is a front perspective view of the garment showing our new design according to a fourth embodiment.

FIG. 38 is a rear perspective view of the garment shown in FIG. 37.

FIG. 39 is a front view of the garment shown in FIG. 37.

FIG. 40 is a rear view of the garment shown in FIG. 37.

FIG. 41 is a right-side view of the garment shown in FIG. 37.

FIG. 42 is a left-side view of the garment shown in FIG. 37.

FIG. 43 is a top view of the garment shown in FIG. 37.

FIG. 44 is a bottom view of the garment shown in FIG. 37.

FIG. 45 is a front view of the garment shown in FIG. 37 when in use.

FIG. 46 is a rear view of the garment shown in FIG. 37 when in use.

FIG. 47 is a front perspective view of the garment shown in FIG. 37 when in use; and,

FIG. 48 is a rear perspective view of the garment shown in FIG. 37 when in use.

The short broken lines showing elements of the garment in the drawings illustrate features of the article of manufacture that form no part of the claimed design. The human figure rendered in short broken lines in FIGS. 9-12, 21-24, 33-36, and 45-48 illustrates environmental subject matter intended to assist in showing how the design appears when in use and forms no part of the claim.
